Wm Bodge

UNITED STATES PATENT OFFICE

CHARLES W. HADDY, OF NEW YORK, N. Y.

PRESSURE REGULATOR

Application filed September 20, 1929. Serial No. 393,967.

The present invention relates generally to pressure-regulators adapted to maintain a desired pressure in steam boilers, more particularly of the oil-burning class in which a variable quantity of oil is fed to the burners of the boiler corresponding to the required steam consumption.

In steamships and other power plants the boilers at times are subject to considerable variation in steam requirements, and where oil is used as fuel constant manual attention frequently becomes necessary to regulate the supply thereof to the burners in order to maintain uniform steam pressure.

The objects of the invention include means actuated by the tendency of variation in boiler steam pressure to cause a corresponding difference in the quantity of oil supplied to the boiler whereby the steam pressure in the latter may automatically tend to remain constant.

A further object is to provide means for regulating the steam pressure in the boiler.

The objects also include a pressure-regulator having its parts closely associated together to form a simplified construction and adapted to quickly respond to changes in steam pressure.

For further comprehension of the invention, and of the objects and advantages thereof, reference is had to the following description and accompanying drawings, and to the appended claims in which the various features of the invention are more particularly pointed out.

Referring to the drawings in which similar characters of reference designate like parts throughout the several views:

Figure 1 of the drawings diagrammatically illustrates in side elevation a steam boiler arranged with oil-feeding and pressure-regulating devices together with pipe connections therefor as embodied in the present invention.

Figure 2 is an enlarged sectional view of the pressure-regulator that controls the steam supply from the boiler to the steam-actuated oil-pump, the latter in turn regulating the quantity of oil fed to the burners of

the boiler whereby the steam pressure therein may be maintained.

As shown in Fig. 1, numeral 10 indicates a steam-boiler provided with oil-burners 11 extending in usual manner into the fire-box 15 of the boiler, the upper portion of the latter having the steam-header 12. A steam-actuated oil-pump is indicated generally at 13, and comprises a steam-cylinder 14 and an oil-cylinder 15, the pistons of the cylinders being connected together by the rod 16. Also, between the steam-boiler and oil-pump is shown an oil-heater 17, and adjacent the oil-pump is disposed a pressure-regulator 18.

As shown in Fig. 2, the pressure-regulator 19 comprises a casing 19, having at one end a detachable cap 20 provided in threaded relation with a hand-screw 21, the opposite end of the casing being threaded to receive an auxiliary steam-connection pipe 22. The casing 19 is exteriorly provided with a valve-body 23, having a screw-cap 24 formed with a conventional stuffing-box and gland through which passes the valve-stem 25, the latter carrying at its lower end a valve-disc 26 arranged in usual manner to seat in the valve-body 23. The casing is also provided with a pair of spaced lugs 27, between which is mounted a lever 28 pivotally supported intermediate its ends by a pin 29 carried by said lugs. At its outer end 30 the lever is connected by a pivot-pin 31 to the upper end of the valve-stem 25. The inner end 32 of the lever extends into the casing 19 through a slot or passage 33 formed in the side wall of the latter, the inner end of the lever being rounded and constituting an operating member for effecting the movement of the valve.

Within the casing 19 is slidably mounted a piston 34 provided with the usual resilient rings 35 for maintaining a close sliding joint with the walls of the casing, and for additionally protecting the piston against leakage a leather cup-packing 36 is provided and secured to the lower end of the piston by the disc 37 and screw 38. At its upper end the piston is formed with a centrally positioned transverse slot 39, adapted to receive in a loose manner the inner end 32 of the lever 28. Above the slot 39 the piston is provided

with a wall 40, the top face thereof constituting the upper end of the piston, and against which face engages the lower end of a spring 41, the upper end thereof being provided with 5 a flanged bearing disc 42 arranged to be engaged by the adjustable hand-screw 21. By means of the latter the tension of the spring may be regulated to downwardly urge the piston in opposition to the upwardly movement effected by the action against the opposite or lower end of the piston of the steam introduced through the pipe 22. The movements of the piston in opposite directions operate by its engagement with the inner end 32 of the lever 28 to correspondingly move the valve disc 26 through the stem 25 and lever-arm 30, thus causing the spring action to open the valve and the steam action to close it. Referring again to Fig. 1, the steam-header 12 is provided with a valve-controlled pipe 43 by means of which steam may be supplied for general use. A main fluid pressure supply pipe 44 also leads from the header 12 to the steam cylinder 14 of the oil-pump 13, and connected to the main pipe are hand valves 45 and 46. Also, connected to the line pipe 44 is a by-pass comprising pipes 47 and 48 having respective valves 49 and 50, and on opening these latter valves and closing valve 45, the steam from the main pipe may pass through the valve-body 23 under control of the pressure-regulator and enter the steam-cylinder 14 through the valve 46 for the operation of the oil-cylinder. The auxiliary steam connection pipe 22 is provided with a stop valve and leads from the relatively large header or drum 12 into the bottom of the pressure-regulator 18, and which portion of the regulator-casing in conjunction with the lower end of the piston 34 constitutes an equalizing chamber 19a adapted to receive steam directly from the header, independently of the main steam supply pipe 44, which latter is subject to a flow of steam therethru 45 of considerable movement, while the steam pressure within the equalizing chamber is relatively quiet, a condition that affords a comparatively steady transmitting action through the piston to the controlling valve of the main supply pipe 44. A steam exhaust pipe 51 provided with a stop-valve 52 is shown leading from the steam cylinder 14, and leading to the oil-cylinder 15 of the oil-pump 13 is a valve controlled oil-pipe 53 adapted to furnish a supply of oil from a convenient source, and leading from the oil-cylinder is a main oil feed pipe 54 extending to the oil-heater 17, and from which point the feed-pipe continues to the burners 11 of the boiler 10. Branch pipes 55 lead from the main pipe to the several burners, and for distributing oil thereto valves 56 are provided for the branches. A stop-valve 57 is provided for the oil feed line adjacent the boiler, and adjacent the oil-cylinder a valve

58 is connected to the line, a safety-valve 59 also being herein shown adjacent thereto for the relief of excessive pressure in the oil line.

In the above described arrangement of parts, the close association and direct action between the pressure-regulator and the steam regulating valve, that controls the speed of the oil-pump, renders the oil supply to the burners of the boiler quickly responsive to any variation of steam pressure, thus enabling the desired boiler pressure to be maintained. In its construction the combined regulator and valve here shown consist of comparatively few parts, readily assembled, or disconnected for repairs. By simply disconnecting a couple of pivot pins the operating lever may be withdrawn from the valve and casing, and the several parts of each quickly removed and replaced. For this purpose no displacement of pipe connections is required, a structural arrangement that lends itself to convenience and speed in the several adjustments.

Furthermore, the present construction provides for the early detection of steam leakage past the piston by allowing the free escape of such leakage through the passage 33 in the casing, the upper end of the piston having a wall adapted to prevent the escaping steam from entering the spring chamber section of the casing and tending to affect the resilience of the spring therein.

I claim:

1. In a pressure regulator, a casing having a passage extending through a side wall thereof, a valve body projecting from said casing and having an extending valve stem, a piston slidable in said casing and provided with an operating slot alined with said passage, and a lever pivotally mounted on said valve body and having its opposite ends respectively engaging in operative relation the walls of said piston slot and said valve stem.

2. In a pressure regulator, a casing having a passage extending through a side wall thereof, a valve body projecting from said casing and having an extending valve stem, a piston slidable in said casing and provided with an operating slot alined with said passage, a lever pivotally mounted on said valve body and having its opposite ends respectively engaging in operative relation the walls of said piston slot and said valve stem, and a spring enclosed within said casing and arranged to effect a variable compression upon said piston.

Signed at New York, in the county of New York and State of New York this sixth day of September A. D. 1929.

CHARLES W. HADDY.
